[57] CLAIM

The ornamental design for a skein holder or the like, as shown and described.

DESCRIPTION

FIG. 1 is a left front perspective view of a skein holder or the like showing my new design;

FIG. 2 is a right side elevational view thereof;

FIG. 3 is a rear perspective view thereof; and

FIG. 4 is a top plan view thereof, the bottom being substantially plain and unornamented.

FIG. I

FIG. 2

FIG. 4
